J. A. STOUGH

TANK ROOF COVERING

Filed July 5, 1924

Patented June 23, 1925.

1,543,131

UNITED STATES PATENT OFFICE.

JAY ALBERT STOUGH, OF TULSA, OKLAHOMA.

TANK-ROOF COVERING.

Application filed July 5, 1924. Serial No. 724,384.

To all whom it may concern:

Be it known that I, JAY ALBERT STOUGH, a citizen of the United States, residing at Tulsa, in the county of Tulsa and State of

5 Oklahoma, have invented certain new and useful Improvements in Tank-Roof Coverings; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to oil tanks and the primary object thereof is to provide a novel form of tank so constructed that liability of oil vapors becoming ignited by "static" sparks will be practically eliminated. It 20 is well known that there is a good deal of "static" about oil tanks and frequently the "static" gaps between the edges of plates, seams or the like provide the necessary spark to ignite the volatile vapors from the oil.

25 My invention contemplates a novel tank construction in which liability of static discharges will be eliminated, this being accomplished by providing a tank wall with a ring like series of cover plates or roof plates and 30 an expansion joint between the ring and the roof covering, the ring being securely fastened to the wall.

The novel construction of the invention will be apparent by reference to the following description in connection with the accompanying drawings, in which—

Fig. 1 is a fragmentary perspective view of a tank constructed in accordance with my invention, and

40 Fig. 2 is a sectional view through part of the roof.

The tank may have the usual wooden supporting structure with the roof boards 2. Above may be constructed the metallic portion of the tank, that is the outer shell. It is shown as comprising a circular wall 3 having an angle 4 at its upper end with a circular ring of roof sheets supported by the boards 2 and by the angle 4.

45 The ring consists of a plurality of segments or members 5 arranged in circular series and secured at their outer edges to the angle 4 by rivets 6 or similar devices, there being a gasket 7 between the angle 4 and the roof sheets 5. The roof sheets or segments 5 are fastened one to the other by bolts 8

or similar means which pass through elongated slots 9 in the overlapping portions of the members 5.

The ring consisting of the members 5 surrounds a central circular space which is adapted to be covered by roofing material 10 of appropriate construction. The edge of the roofing material 10 is spaced from the inner edge 11 of the ring but there is an expansion joint formed between the two. This is made by securing a flexible fabric or similar web 12 to the members 5 by a cleat or cleats 13 and by lapping the inner edge 14 of the flexible sheet under the roof sheet 10 and upon the blocks 15 where the roof sheet 10 and the flexible web may be fastened to the blocks by fastening devices 16.

A ring or rings 17 of wire rope or similar material may rest within the fold 18 in the expansion joint so that the joint will tend to maintain the open loop position shown in Fig. 1. The tank may therefore expand and contract without opening seams and providing spark gaps across which the static of 80 electricity may jump to provide the spark which is necessary to combust the highly volatile gases. All fittings such as the gauge hole cover 19 and the like are provided on the metallic ring.

It will be apparent from the foregoing that a tank constructed in accordance with my invention will not provide sparks tending to ignite the volatile fluid and that the roof may be supported upon the posts 1, the 90 rafters 20 and roof boards or sheathing boards 2 in a novel manner to permit expansion and contraction without danger of ignition of the gases taking place due to the construction of the tank. The tank walls and 95 roof are so formed that any static will necessarily be grounded and this of course eliminates the chance of accidental ignition of the gases.

What I claim and desire to secure by Letters-Patent is:—

1. A tank comprising a wall, a plurality of segments connected to the wall at the edge thereof and arranged in circular series, roofing material inside the space surrounded 105 by the ring and a flexible connection between the roofing material and the inner edge of the ring.

2. A tank comprising a wall, a plurality of segments connected to the wall at the edge thereof and arranged in circular series, roofing material inside the space surrounded 110

by the ring and a flexible connection between the roofing material and the inner edge of the ring, said connection comprising a web fastened to the edges of the ring and to the 5 roofing material.

3. A tank comprising a wall, a plurality of segments connected to the wall at the edge thereof and arranged in circular series, roofing material inside the space surrounded 10 by the ring, a flexible connection between the roofing material and the inner edge of the ring, said connection comprising a web fastened to the edges of the ring and to the roofing material, and a member inside the 15 fold of the web to maintain its position with respect to the ring and to the roofing material.

4. A tank comprising a wall, a plurality of segments connected to the wall at the edge thereof and arranged in circular series, 20 roofing material inside the space surrounded by the ring, a flexible connection between the roofing material and the inner edge of the ring, said connection comprising a web fastened to the edges of the ring and to the 25 roofing material, a member inside the fold of the web to maintain its position with respect to the ring and to the roofing material, and a fitting fastened to the ring so as to be outside the periphery of the roofing material. 30

In testimony whereof I affix my signature.

JAY ALBERT STOUGH.
